UNITED STATES PATENT OFFICE

CARLO GIANINI, OF ROME, ITALY

DESIGN FOR A COMBINED CLOCK CASE AND RADIOCABINET

Application filed August 12, 1929, Serial No. 32,394, and in Italy April 11, 1929. Term of patent 3½ years.

To all whom it may concern:

Be it known that I, CARLO GIANINI, a subject of the King of Italy, residing at Rome, Italy, have invented a new, original, and ornamental Design for a Combined Clock Case and Radiocabinet, of which the following is a specification, reference being had to the accompanying drawing, forming a part hereof, in which—

Fig. 1 is a side elevation of a combined

clock case and radiocabinet, showing my new design; and Fig. 2 is a front view of the same.

I claim:

The ornamental design for a combined clock case and radiocabinet, substantially as shown.

In witness whereof I have hereunto set my signature.

ING. CARLO GIANINI.
